[57] CLAIM

The ornamental design for a truck, substantially as shown and described.

DESCRIPTION

FIG. 1 is a front elevational view of a truck showing my new design;

FIG. 2 is a side elevational view thereof to a reduced scale;

FIG. 3 is a side elevational view thereof to a reduced scale of the side opposite to that shown in FIG. 2; and FIG. 4 is a perspective view thereof to a greatly reduced scale.

The rear of the truck is substantially flat and unornamented.

FIG. 1

FIG. 2

FIG. 3

FIG. 4
